(57) **CLAIM**

The ornamental design for a mount for an infant receiving device, as shown and described.

DESCRIPTION

FIG. 1 is a front perspective view of a mount for an infant receiving device according to the present invention illustrated on the frame of an infant swing;

FIG. 2 is rear view of the mount for an infant receiving device of FIG. 1;

FIG. 3 is a front view of the mount for an infant receiving device of FIG. 1;

FIG. 4 is a right side view of the mount for an infant receiving device of FIG. 1;

FIG. 5 is a left side view of the mount for an infant receiving device of FIG. 1;

FIG. 6 is a top view of the mount for an infant receiving device of FIG. 1; and,

FIG. 7 is a bottom view of the mount for an infant receiving device of FIG. 1.

The portions shown in phantom are for illustrative purposes only and form no part of the claimed design.
